TO DOUBLE BODY BOLSTER COMPANY, OF ST. LOUIS, MISSOURI, A CORPORATION OF
NEW JERSEY.

CAR CONSTRUCTION.

1,039,043.

Specification of Letters Patent. Patented Sept. 17, 1912.

Original application filed July 3, 1911, Serial No. 636,762. Divided and this application filed February 17, 1912. Serial No. 678,394.

To all whom it may concern:

Be it known that we, CHARLES F. FREDE and CHARLES T. WESTLAKE, citizens of the United States, residing at St. Louis, Missouri, have invented a certain new and useful Improvement in Car Construction, of which the following is a full, clear, and exact description, such as will enable others skilled in the art to which it appertains to make and use the same, reference being had to the accompanying drawings, forming part of this specification, in which—

Figure 1 is a plan view of a portion of a combined cast metal platform and double body bolster of the type usually employed in connection with underframes of blind end cars and illustrating our improved construction in connection therewith. Fig. 2 is an enlarged cross section taken on the line 2—2 of Fig. 1. Fig. 3 is a vertical section taken on the line 3—3 of Fig. 2. Fig. 4 is a horizontal section taken on the line 4—4 of Fig. 2.

This invention relates generally to car construction and particularly to the means employed for rigidly connecting the lower ends of the vestibule posts to the buffing sill of the car underframe, and the subject matter forming this application in a division of the subject matter disclosed in an application filed by us July 3, 1911, Serial No. 636,762.

In passenger car construction of the present type, it is to a large extent the practice to utilize combined cast steel platforms and double body bolsters, and it is the object of our invention to connect the lower ends of the vestibule posts to the buffing sill of the platform in a manner so as to provide a very strong rigid construction particularly adapted to withstand end shocks and buffing strains to which the end walls and vestibule walls are subject during service.

A further object of our invention is to provide a construction wherein the lower ends of the vestibule posts are extended

downward through openings formed in the top and bottom walls of the buffing sill and which openings are arranged so that the strength of said sill is not materially weakened, and further to provide vertically disposed walls and reinforced strengthening flanges on the buffer beam adjacent to the openings therein for the purpose of maintaining the strength of said sills at the points where the vestibule post openings are formed.

To the above purposes, our invention consists in certain novel features of construction and arrangement of parts hereinafter more fully described and claimed.

Referring by numerals to the accompanying drawings, 10 designates the main body of the combined platform and double body bolster and formed integral with the end 65 thereof is the buffer beam 11 which is of the ordinary hollow box type.

Formed through the top plate of the buffing sill 11 are openings 12 of such size as to readily receive the vestibule posts 13, which, as shown, are in the form of I-beams. The top plate of the buffing sill 11 extends inwardly at one side of each opening 12 and positioned upon this extension and fixed thereto by means of rivets is the horizontally disposed leg of an angle bracket 14, the vertical leg of which is riveted to the web of the corresponding vestibule post. Formed through the bottom plate of the buffing sill is an opening 15 preferably so T-shaped through which projects the lower end of the vestibule post and the forward lower corner of said post is notched or cut away as designated by 16 in order to accommodate that portion of the bottom plate 85 of the sill immediately in front of the corresponding opening 15. Such construction does away with the necessity of cutting an opening entirely across the bottom plate of the buffing sill which would materially weaken the buffing sill at this point. By notching the lower end of the vestibule post

and extending the bottom plate of the buffing sill rearwardly, a strong substantial construction is produced and the strength of the buffing sill is retained.

5. Formed integral with the top and bottom plates of the buffing sill and extending between the extension on which the angle bracket is fixed and the bottom plate of the buffing sill to the side of the opening 15 is 10 a vertically disposed strengthening web 17. Formed integral with the bottom plate of the buffing sill to the side of the opening 15 and preferably in alignment with the web 17 is a depending flange 18 which is reinforced by integral triangular webs 19, and that portion of the lower end of the vestibule post which extends through the opening 15 is connected to this flange 18 by means of rivets or like fastening devices.
20. The lower portion of each vestibule post, or that portion which extends through the buffing sill, is offset on its rear side as designated by 20 so that the rear face of the rear flanges of each post above the buffing 25 sill are flush with the rear face of the rear vertical wall of said sill.

Our improved construction is comparatively simple, is particularly adapted for all types of cars utilizing combined cast steel 30 platforms and double body bolsters and provides a very strong, rigid construction between the vestibule posts and the buffing sill.

The body of each vestibule post is connected to the buffing sill at points substantially above and below the top and bottom plates of said buffing sill and the lower ends of the posts are cut away in order that the bottom plate of the buffing sill can be extended rearwardly from the front wall a sufficient distance to provide the requisite strength for said sill at points where the posts connect therewith.

It will be readily understood that minor changes in the size, form and construction of our improved car construction can be made and substituted for those herein shown and described without departing from the spirit of our invention, the scope of which 50 is set forth in the appended claims.

We claim:

1. In car construction, a hollow cast metal buffing sill provided with aligned openings in its top and bottom plates adapted to receive the lower ends of the vestibule posts of the car superstructure, and integral reinforcing webs within the buffing sill adjacent to the openings therein.

2. The combination with a car under-frame buffing sill having top and bottom plates through which are formed openings, of a vestibule post the lower end of which is seated in said openings and fixed to the top and bottom plates of said sill, and the lower

end of which post is notched to accommodate the bottom flange or plate of the buffing sill.

3. The combination with a car under-frame buffing sill through which is formed a vertically disposed opening, of a vestibule post the lower end of which extends through said opening, a bracket projecting upwardly from the top plates of the sill, a bracket depending from the bottom plate of said sill, and fastening means passing through said brackets and the vestibule post.

4. The combination with a car under-frame buffing sill having a comparatively wide opening formed through its top plate and a comparatively narrow opening formed 80 through its bottom plate, of a vestibule post the lower end of which passes through the openings in the top and bottom plates of the buffing sill, and the lower end of which vestibule post is cut away so as to occupy 85 the opening in the bottom plate of said buffing sill.

5. The combination with a car under-frame buffing sill, provided with openings through its top and bottom plates, of a vestibule post having its lower end seated in said openings, a strengthening web integral with the buffing sill adjacent the openings therein and means including brackets on the top and bottom plates of the buffing sill whereby the 95 post is rigidly fixed to the sill.

6. The combination with a car under-frame buffing sill provided with openings in its top and bottom plates, of a vestibule post fixed to said buffing sill with its lower 100 end positioned in the openings, an integral web connecting the top and bottom plates adjacent to the openings therein, a flange integral with the bottom plate to the side of the opening therein, and means whereby said 105 post is fixed to the buffing sill and to the flange on the bottom plate thereof.

7. In car construction, a hollow cast metal buffing sill provided with aligned openings 110 through its top and bottom plates adapted to receive the lower portions of vestibule posts, and integral brackets depending from the bottom plate of the buffing sill, which brackets bear against and provide means for attaching the extreme lower ends of the 115 vestibule posts.

8. The combination with a car under-frame buffing sill provided with openings in its top and bottom plate, of a vestibule post, the lower end of which extends through 120 the openings in the buffing sill, and the lower front corner of which post is cut away to receive the portion of the bottom plate which is immediately in front of the opening through said bottom plate.

9. The combination with a cast metal buffing sill provided with openings adapted 125 to receive the lower portions of vestibule

posts, of attaching means projecting upwardly from the top plate of the buffering sill and engaging the lower portions of the vestibule posts, and attaching means depending from the underside of the buffering sill for engaging the lower ends of said vestibule posts.

In testimony whereof we hereunto affix

our signatures in the presence of two witnesses, this 5th day of February, 1912.

CHARLES F. FREDE.
CHARLES T. WESTLAKE.
